UNITED STATES PATENT OFFICE.

DAVID E. PLATTNER, OF BRADFORD, PENNSYLVANIA, ASSIGNOR OF ONE-HALF TO
RICHARD L. HIGGINS, OF BRADFORD, PENNSYLVANIA.

WINDOW-SHADE HOLDER.

1,317,313.

Specification of Letters Patent. Patented Sept. 30, 1919.

Application filed October 25, 1916, Serial No. 127,627. Renewed July 26, 1919. Serial No. 313,478.

To all whom it may concern:

Be it known that I, DAVID E. PLATTNER, a citizen of the United States, residing at Bradford, in the county of McKean and State of Pennsylvania, have invented certain new and useful Improvements in Window-Shade Holders, of which the following is a specification, reference being had to the accompanying drawings.

10 This invention relates to an improved window shade holder and has for its primary object to provide simple means for mounting and supporting the window shade, whereby the same may be bodily raised or lowered so as to provide ventilation at the top of the window while covering the lower portion thereof.

It is another object of the invention to provide a device of the above character which is simple in its construction, efficient and reliable in operation, and capable of manufacture at relatively small cost.

It is another important object of my invention to provide means for applying the shade holder to the window frame, whereby the necessity of marring the face of the frame or breaking the plastering is obviated.

With the above and other objects in view, my invention consists in the novel features of construction, combination and arrangement of parts to be hereinafter more fully described, claimed and illustrated in the accompanying drawings, in which,

Figure 1 is an elevation illustrating the preferred embodiment of my improved shade holder applied to a window frame;

35 Fig. 2 is a top plan view;

Fig. 3 is an edge view; and

Fig. 4 is a section taken on the line 4—4

40 of Fig. 2.

Referring in detail to the drawing, 5 indicates a metal rod which is adapted to be disposed longitudinally upon the upper edge of the window frame indicated at F. This rod is provided at its ends with apertures to receive suitable fastening screws 6.

Upon the rod 5, adjacent each end thereof, the sleeves 8 formed in one end of the bracket members 7, are engaged. These bracket members extend downwardly over the face of the window frame and upon the lower end of each bracket, a guide roller or sheave 9 is rotatably mounted.

The shade roller support consists of two

55 ably constructed from a single plate of sheet metal. The member 10 has its longitudinal edge portions bent into spaced, parallel relation to the body of the plate, as at 12, to provide guides for the other supporting member 11. Thus, these members may be moved in relatively opposite, longitudinal directions and extended in accordance with the width of the window frame. Each of the supporting members is provided upon one 60 end with an angularly disposed arm 13 and 14 respectively, one of said arms having a circular opening therein and the other being provided with a slot in the usual manner to receive the trunnions on the ends of the 70 shade roller indicated at R.

A metal ring 15 is suitably connected to each of the members 10 and 11, adjacent their outer ends, and to these rings the adjusting cords 16 are attached. The cords 16 75 may be tied or knotted together at intervals, as indicated at 17, to coöperate with a fastener fixed in one edge of the frame F. This fastener consists of a length of resilient wire bent to provide spaced loops 18 therein. 80 The terminals of the wire are driven into the frame F and the loops 18 extend horizontally therefrom.

In the use of the device, it will be understood that when it is desired to ventilate the 85 apartment, the cords 16 are detached from the fastener so that the shade roller and its support will drop downwardly, the cords 16 moving over the spaced guide rollers 9. When the shade has been lowered to the 90 proper position, one of the knots 17 is engaged beneath the opposed portions of the spaced loops 18, the cords 16 being tightly clamped by said loops. The upper sash may now be lowered. In this manner, the 95 room or apartment can be thoroughly ventilated, while the lower portion of the window is covered by the shade. The shade is withdrawn from the roller in the usual manner, and when the roller is at the top of the 100 window frame, the shade may be extended so as to cover the entire window.

From the foregoing description, taken in connection with the accompanying drawing, the construction, manner of operation and 105 several advantages of the invention will be clearly and fully understood. The device, while exceedingly simple, is efficient in its operation, as well as serviceable and convenient in practical use. It will be under- 110

stood that the bracket members 7 may also be adjusted upon the rod to any desired position, in accordance with the width of the window. By mounting the device upon the window frame in the manner referred to, the face of the frame is not marred by driving screws or nails therein, or the wall plastering damaged. In view of the very simple construction of the several elements employed, it will also be appreciated that the invention may be produced at small manufacturing cost.

While I have shown and described the preferred construction and arrangement of the several parts, it is to be understood that the invention is susceptible of considerable modification therein and I, therefore, reserve the privilege of adopting all such legitimate changes as may be fairly embodied within the spirit and scope of the invention as claimed.

Having thus fully described my inven-

tion, what I desire to claim and secure by Letters Patent is:—

In combination, a fixed rod secured upon the upper edge of a window frame, a pair of bracket members each having a portion encircling the rod for longitudinal adjustment along the same and one end of the bracket extending downwardly over the face of the window frame, a guide sheave mounted upon the lower end of each bracket, a shade roller support, and flexible elements connected to said support at the ends thereof and extending over said guide sheaves whereby said support may be vertically adjusted with respect to the fixed rod.

In testimony whereof I hereunto affix my signature in the presence of two witnesses.

DAVID E. PLATTNER.

Witnesses:

GEORGE M. CRANDALL,
JOSEPH BURGER.
